UNITED STATES PATENT OFFICE.

DAVID M. HORTON, OF FISHKILL, NEW YORK.

HEATING APPARATUS.

SPECIFICATION forming part of Letters Patent No. 736,099, dated August 11, 1903.

Application filed March 10, 1902. Serial No. 97,472. (No model.)

To all whom it may concern:

Be it known that I, DAVID M. HORTON, a citizen of the United States, and a resident of Fishkill, in the county of Dutchess and State of New York, have invented a new and Improved Heating Apparatus, of which the following is a full, clear, and exact description.

This invention relates to certain novel features of construction for enabling me to heat various apartments in a building from a single stove or furnace. It is particularly adapted to domestic use, and it is here shown as applied to an ordinary heating-stove in a lower room, with provision for heating one of the rooms above.

Of course the heating apparatus could be extended to two or to any number of rooms without departing from the principles of my invention.

This specification is an exact description of two forms of my invention, while the claims define the actual scope thereof.

Reference is to be had to the accompanying drawings, forming a part of this specification, in which similar characters of reference indicate corresponding parts in all the views.

Figure 1 is a sectional view of the apparatus. Fig. 1^a is a detail section showing the deflector, and Fig. 2 is a sectional view showing a modified arrangement of the apparatus.

Referring to Figs. 1 and 1^a, *a* indicates the lower room, in which is situated the stove or heater *b*, and *a'* indicates the room above. *c* indicates the flue or chimney of the building, and *d* the ordinary stovepipe leading from the heater *b* into the flue. Directly opposite the outlet of the pipe *d* and within the flue *c* is located the concavo-convex drum-like 35 deflector *e*, (best shown in Fig. 1^a), the concave side of the deflector-drum being directly opposite the mouth of the pipe *d*, so that the hot gases passing from this pipe strike against the concave side of this drum and are deflected 40 in all directions from the same, thus effectively applying the heat of said gases to said drum. Communicating with the upper and lower portions of the drum are pipe-sections *f* and *f'*, the section *f* extending downward in the 45 flue and communicating with the lower part of the room *a* by means of a register or other

controlling apparatus *f*². The pipe-section *f'* extends upward and leads into the room *a'* by way of a register or the like *f*³. Located within the stovepipe *d* is a pipe *g*, which has 5; its lower end turned laterally, as indicated at *g'*, and passed through the walls of the pipe *d* into communication with the room *a*. The other end of the pipe *g* projects through the discharge end of the pipe *d* into the flue 60 *c* and through the concave wall of the drum *e*, so as to communicate with the interior of the drum. From the pipe *g* within the stovepipe *d* leads a branch *g*², which extends upward through the floor of the room *a'* and communicates therewith by a register or the like *g*³. The heated gases passing from the stovepipe *d* will impinge directly against the drum *e* and thoroughly heat the same, and then in passing up the flue will heat the pipe-section 70 *f*. The pipe-section *f* draws in air from the room *a*, and this air is passed through the drum *e* to be thoroughly heated, after which it passes up by the pipe-section *f'* into the room *a'*. Air is also drawn in at the point *g'* by 75 the pipe *g* from the room *a* and from room *a'* through register *g*³ and pipe *g*², and this air passes up to the drum *e* and up section *f'* and through register *f*³ into room *a'*, the air in pipe *g* being meanwhile heated by the 80 burning gases within the pipe *d*. Dampers or other means for controlling the passage of the air and gases in one direction or the other may be provided, as desired, and since these are matters of ordinary mechanical skill they 85 have not been here illustrated.

The form of the invention shown in Fig. 2 embodies a drum *e'*, similar to the drum *e*, and a pipe-section *f*⁴, similar to the pipe-section *f*'. The stovepipe *d* in Fig. 2 has an air-tube *g*⁴ 90 therein, which leads directly to the drum *e'*. In this modified form of the invention the pipe-section *f* and branch *g*² with their apertures are omitted. In other respects the principle of the device is the same as that 95 before described.

Various changes in the form and details of my invention may be resorted to at will without departing from the spirit of my invention. Hence I consider myself entitled to all forms 100 of the invention as may lie within the intent of my claims.

Having thus described my invention, I claim as new and desire to secure by Letters Patent—

1. The combination with the building and the smoke-flue thereof, of a heater in one room of the building, a pipe leading the burning gases therefrom and discharging into the flue, a drum located within the flue opposite the said pipe to be heated by the gases therefrom, an air-pipe in the stovepipe and having one end leading through the wall of the pipe and its other end projecting through the discharge end of said pipe and opening into the said drum, and a pipe leading from the drum to another apartment of the house.
2. The combination with the building and the smoke-flue thereof, of a heater in one room of the building, a pipe leading the burning gases therefrom and discharging into the flue, a drum located within the flue opposite the said pipe to be heated by the gases therefrom, an air-pipe in the stovepipe and having one end leading through the wall of the pipe and its other end projecting through the discharge end of said pipe and opening into the said drum, a pipe leading from the drum to another compartment of the house, and an additional pipe leading from the drum downward through the flue and thence into the first-named room, to draw air therefrom, for the purpose specified.
3. The combination with the building and the smoke-flue thereof, of a heater in one room of the building, a pipe leading the burning gases therefrom and discharging into the flue, a drum located within the flue opposite the said pipe to be heated by the gases therefrom, an air-pipe leading from said room through the stovepipe and communicating with the interior of the drum, a pipe leading from the drum to another compartment of the house, and a branch pipe extending from the air-pipe within the stovepipe outward from the stovepipe and into said second compartment.
4. The combination with the building and the smoke-flue thereof, of a heater in one room of the building, a stovepipe passing therefrom into the flue, a concavo-convex drum located in the flue with its concave side opposite the discharge of the stovepipe to be heated by the gases therefrom, an air-pipe passing from the room through the stovepipe and communicating with the interior of the drum, a branch pipe extending from the air-pipe into a second room of the building, a pipe-section run-

ning through the flue from the drum to said second room of the building, and an additional pipe-section located in the flue and extending from the first-named room and communicating with the interior of the drum.

60

5. In a heating apparatus of the character described, the combination with the smoke-pipe of a heater, of a concavo-convex drum adapted to be arranged in the smoke-flue or chimney with its concave side opposite the smoke-pipe of the heater, an air-pipe arranged in the smoke-pipe and having one end opening through the wall of the smoke-pipe in the room in which the heater is located, and its other end opening into the drum through the concave side thereof, and a pipe leading from the drum for conveying the hot air from the drum to a room above that in which the heater is arranged.

65

6. In a heating apparatus of the character described, the combination with the smoke-pipe of a heater, of a concavo-convex drum adapted to be located in the smoke-flue or chimney with its concave side opposite the smoke-pipe, an air-pipe arranged in the smoke-pipe and having one end passed through the wall of the pipe and its other end opening into the drum through its concave side, and pipes leading from opposite sides of the drum, one of said pipes conveying air from the room in which the heater is located to the drum and the other conveying the hot air from the said drum to an upper room of a building.

70

7. In a heating apparatus of the character described, the combination with the smoke-pipe, of a heater, of a concavo-convex drum adapted to be arranged in the smoke-flue or chimney, with its concave side opposite the smoke-pipe, an air-pipe arranged in the smoke-pipe and having one end passed through the wall of the pipe and its other end projecting through the discharge end of said pipe and opening into the drum through its concave side, pipes leading from opposite sides of the drum for admitting air to and conveying air from said drum, and a pipe leading from the air-pipe out through the smoke-pipe.

75

In testimony whereof I have signed my name to this specification in the presence of two subscribing witnesses.

DAVID M. HORTON.
